SASH LOCK

Edward H. Gavie, Addison, Ill.

Application July 17, 1933. Serial No. 680,723

1 Claim. (Cl. 292—251)

My invention relates to a sash lock,—more particularly a lock for the sash of double hung windows.

The present invention provides a sash lock which in its preferred embodiment comprises but three principal parts, i. e., a special locking screw and a pair of sash-carried sleeves by which such special screw is carried and with which it operates. All parts of the lock lie below the upper surfaces of the sash rails by which the lock elements are carried. The lock, when its screw is in its locking position, serves to draw the contiguous sash rails tightly into engagement with each other in addition to preventing relative sliding movement between the sash.

The locking screw and its cooperating sash-carried sleeves are so constructed and arranged that the screw always has threaded engagement with at least one of said sleeves, regardless of whether the screw is in its locking or non-lock-position. The several elements of the lock are of simple construction, economical to manufacture, and easy to install.

Other features, objects and advantages of my invention will appear from the following detailed description, wherein reference is made to the accompanying sheet of drawings, in which

Fig. 1 is an inside elevational view of a window provided with the sash lock of my invention;

Fig. 2 is a fragmentary sectional view, on larger scale, which may be regarded as taken on the line 2—2 of Fig. 1, looking in the direction indicated by the arrows;

Fig. 3 is a view similar to Fig. 2, but illustrating a slightly modified embodiment of my invention; which said Fig. 3 may be regarded as taken on the line 3—3 of Fig. 1 and looking in the direction indicated by the arrows;

Fig. 4 is a fragmentary view partly in section and partly in elevation, which may be regarded as taken on the line 4—4 of Fig. 2 and looking in the direction indicated by the arrows; and

Fig. 5 is a fragmentary inside elevational view which may be regarded as taken in the plane of the lines 5—5 of Fig. 2, looking in the direction indicated by the arrows.

Similar characters of reference refer to similar parts throughout the several views.

Referring first to Figs. 1 and 2, at 6 I have illustrated a window frame within which the upper sash 7 and the lower sash 8 are hung and guided for independent vertical sliding movements in the conventional or any suitable manner. One of the parting strips with which dou-

ble hung sash frames are usually provided is indicated at 9 in Figs. 2 and 3.

It will be noted that the lower rail 10 of the upper sash and the upper rail 11 of the lower sash are provided with complementary faces 12 and 13 which are adapted to be locked and drawn snugly into opposition by means of the sash lock now to be described.

Referring now to Fig. 2, it will be seen that the lower rail 10 of the upper sash is recessed, midway between its ends, to receive an internally threaded metal sleeve 14, the axis of which is disposed at right angles to the said sash rail. The sleeve 14 is provided with an integral attachment flange 15, which is countersunk in the inner face of the rail 10 and is preferably retained in position by screws 16—16.

Formed in the upper rail 11 of the lower sash, midway between its ends, and having its axis at right angles to said rail, is a bore 17, the left hand end (Fig. 2) of which is disposed in exact alignment with the bore of the sleeve 14 when the sash are in the fully closed positions illustrated in Fig. 2.

The bore 17 is enlarged at its inner or right hand end (Fig. 2) to receive a metal sleeve 18, which is preferably provided with an integral attachment escutcheon 19, which is secured to the inner surface of the sash rail 11 by screws 20—20. The inner surface of the sleeve 18 is threaded for a short distance from left to right (Fig. 2), as indicated at 21, the remainder of the inner surface of said sleeve being smooth, as indicated at 22.

Carried by and cooperating with the sleeves 14 and 18 is a special locking screw indicated as a whole at 23. Said locking screw 23 comprises four distinct parts, namely the handle portion 24, the cylindrical portion 25, the reduced portion 26, and the elongated threaded portion 27.

When the sash and lock parts are in the positions shown in Fig. 2, the portion 25 of the special screw lies within the unthreaded portion 22 of the sleeve 18, the reduced portion 26 of the screw clears the threads 21 of the sleeve 18, and the threaded portion 27 of the screw is in engagement with the internal threads of the sleeve 14. The handle portion 24 of the screw preferably has a shoulder 28, which bears against the escutcheon 19 when the parts are in the relative positions shown in Fig. 2. It will thus be seen that turning of the handle 24 in the clockwise direction from a position of Fig. 2 will result in drawing the opposed faces 12 and 13 of the sash bars tightly into engagement.

With the sash and the several lock elements in the positions shown in Fig. 2, the sash are held against relative sliding movements. When it is desired to unlock the sash, the special screw 23 is turned in the counterclockwise direction until the threaded portion 27 of the screw has been entirely disengaged from the sleeve 14 of the upper sash. It will be observed, however, that it is impossible entirely to disengage the screw 16 from the sleeve 14 without having the threaded portion 27 of the screw engage the threaded portion 21 of the sleeve 18 of the lower sash. By reason of the fact that the threaded portion 27 of the screw must at all times engage the internal threads of one or both of the sleeves 14 and 18, there is no danger of the screw being accidentally withdrawn or shaken out of the upper bar 11 of the lower sash when the screw is occupying its non-locking position.

In the modified embodiment of my invention illustrated in Fig. 3, the transverse bore 17 of the upper bar 11 of the lower sash is of uniform diameter throughout its length, i. e. equal to the outer diameter of the sleeve 18. With the bore 25 17 thus enlarged in diameter, it is possible to provide the threaded portion 27 of the screw with a cross pin 30 which is adapted to engage the inner or left hand end (Fig. 3) of the sleeve 18 when the screw is entirely out of engagement 30 with the sleeve 14 of the upper sash. The engagement of the cross pin 30 with the inner end of the sleeve 18 serves to advise the operator that the locking screw is in a position such that it is both possible and safe to move either one of the 35 sashes relative to the other, and also prevents further turning of the screw in the counterclockwise direction after the screw has assumed its non-locking position.

The cylindrical portion 25 of the screw has a working fit in the cylindrical portion 22 of the sleeve 18, thereby assuring the accurate location of the screw to register with the sleeve 14.

Having thus illustrated and described my invention in two preferred embodiments thereof, what I claim is new and desire to secure by Letters Patent of the United States is:

In combination with meeting rails of a pair of double hung sash, an internally threaded sleeve carried by the outer rail and extending from the inner face thereof partly into said rail, a sleeve located in the forward part of the inner rail within a bore extending through said rail, adapted to lie in alignment with the sleeve in the outer rail in closed position of the sashes, the last said sleeve having a cylindrical portion at its inner end and a threaded portion at its outer end, a screw adapted to lie within said sleeves and within said bore, said screw comprising a threaded portion at its outer end adapted threadedly to engage the threaded portion of either sleeve, a handle portion at its inner end, an overhanging portion adjacent said handle adapted to abut the outer end of the sleeve carried by the inner rail, a cylindrical portion adapted to have a working fit in the cylindrical portion of the last said sleeve, an intermediate portion connecting the cylindrical portion to the threaded portion of said screw, and an abutment means carried by said screw, at an intermediate portion of the threaded portion thereof, adapted to abut against the outer end of the sleeve carried by the inner rail when the screw is moved to unlocked position.

EDWARD H. GAVIE.
